UNITED STATES PATENT OFFICE.

FRITZ DEIMEL, OF BERLIN, GERMANY.

ROTARY FLOAT.

SPECIFICATION forming part of Letters Patent No. 439,124, dated October 28, 1890.

Application filed December 3, 1889. Serial No. 332,410. (No model.) Patented in Germany April 14, 1889, No. 49,760; in France July 16, 1889, No. 199,621; in Norway August 23, 1889, No. 1,481; in Belgium September 7, 1889, No. 87,661; in Italy September 30, 1889, No. 26,055/461; in England October 26, 1889, No. 13,076; in Switzerland November 27, 1889, No. 1,520, and in Austria-Hungary December 30, 1889, No. 36,126 and No. 64,578.

To all whom it may concern:

Be it known that I, FRITZ DEIMEL, a subject of the King of Prussia, residing in Berlin, Germany, have invented certain new and useful Improvements in Rotary Floats, (for which I have obtained patents in Germany April 14, 1889, No. 49,760; in France July 16, 1889, No. 199,621; in Austria-Hungary December 30, 1889, No. 36,126 and No. 64,578; in Norway August 23, 1889, No. 1,481; in Italy September 30, 1889, No. 26,055/461; in Great Britain October 26, 1889, No. 13,076; in Switzerland November 27, 1889, No. 1,520, and in Belgium September 7, 1889, No. 87,661,) of which the following is a full, clear, and exact description.

The usual form of floats, which act merely by their buoyancy, present the disadvantage that they must be of a comparatively very large size if the closing of the inlet-opening which is effected by them shall be assured at all times and under all circumstances. If such a float is to be used in a fluid of a very small density and specific weight, it must have such large dimensions, if it is to effect a somewhat tight closing of the inlet, that its practical use is very limited.

The present invention has for its object to construct a float having water-deflecting guides or conduits, which is rotated by the action of the liquid on said guides and thus effects a tight and perfect closing of the valve which the float operates. The float may also have combined with it a screw by which said rotation causes it to be raised to operate the valve independently of the mere buoyancy of the float.

In the annexed drawings, which form a part of this specification, Figure 1 is a side elevation of my improved float, showing the same in position within a reservoir. Figs. 2 and 3 are plan views of modified forms of the float. Figs. 4, 5, 6, 7, and 8 also show modified forms of the float and valve mechanism.

The float B rests in the receptacle A, which carries on its bottom a small inwardly-threaded tube a. This float is usually hollow and has a conical or spherical shape. Its surface

is provided with sloping or turbine-like ribs 50 b b', or with oblique or curved grooves. At the bottom of the float B is arranged a threaded stud d, fitting into the inwardly-threaded tube a, and preferably provided at its lower end with a guide-pin e, which will materially facilitate the adjustment of the float. At the upper end of the float is adjusted a little cone k, which when in the required position will close the mouth of the inlet f when the cover C of the reservoir is put in place. For the same purpose, as heretofore explained, it is preferable to provide the cone k also with a guide-pin g.

The outlet D of the reservoir A can be arranged at any suitable place. If the inlet is 65 open and the level of the fluid in the reservoir A is to be stationary while the discharge of the fluid from the reservoir is irregular, the float B will regulate the feeding in the following way: The liquid entering through 70 the inlet flows upon the float B and presses the ribs b b', thereby rotating the float. The weight of the float will prevent the rotation until the liquid rising in the reservoir A will lighten the float so that the driving-power of 75 the entering liquid will be the stronger. The float B consequently rotates and is screwed upward by means of its stud arranged in the inwardly-threaded tube a until the cone k will have regulated the feed-opening in correspondence with the discharge of the liquid.

If the discharge-opening D is closed, the inlet will also be closed automatically by the two forces acting upon the float—viz., the buoyancy of the float and the inflowing rotary force created by the action of the entering liquid upon the ribs of the float. The combination of these two forces will cause a perfectly tight and effective closing of the inlet-opening.

A further important feature of this float is that in consequence of the rotation the closing-cone will be automatically kept clean, and thus be able to close the inlet tightly and effectively.

Instead of the arrangement just described, the closing device can be constructed as shown in Fig. 5.

The elastic closing-plate *i*, provided with a solid pressing-plate *h*, is guided in a suitable manner in the inlet-tube *f*, and the float *B* carries at its upper end a plain stud *k'* instead of the cone *k*.

Instead of arranging the threaded rod *d* in the center of the float, as is done in the constructions shown in Figs. 1 and 4, it can also be arranged in the periphery of the float *B*, Fig. 5, in which case the liquid surrounding the float acts as a nut. When the float is raised by the ascending force of the flowing liquid, the screw-thread arranged on the periphery of the float will act just like the thread-stud *d*, Figs. 1 and 4, is acting, in combination with the inwardly-threaded tube. Consequently the float *B* is not merely raised while rotating, but it screws itself upward in the surrounding liquid. The stud *k'* presses the closing-plate against the mouth of the inlet in such an effective way, in consequence of the spiral action of the float, that in this construction, I likewise obtain a perfectly-tight closing.

Instead of arranging the closing-plate at the mouth of the inlet, it can, as shown in Fig. 8, be connected directly with the stud *k'*. In this case the closing-plate must be connected with the stud so as to be allowed a rotary motion, so that the stud can rotate without carrying along the plate, as otherwise the plate would be soon spoiled.

When the screw-thread is arranged on the periphery of the float, Fig. 4, the sloping or turbine-like ribs *b b'*, Figs. 2 and 3, can be dispensed with, as the screw-thread will have the same effect as said ribs.

As the above-mentioned sloping ribs have only for their object to rotate the float *B* through the medium of the entering liquid, they can of course be replaced by other suitable arrangements having the same effect. In the constructions shown in Figs. 6 and 7, I attain this purpose by inserting reaction-

tubes. The screw around the float on the threaded stem under the float can also be replaced by other suitable devices having the same effect. The screw *d* may, if desired, be formed upon the upper end of the float and engaged with a correspondingly-threaded part carried by the inlet-pipe, as shown in Fig. 4.

Having fully described my invention, what I claim as new, and desire to secure by Letters Patent, is as follows:

1. A float provided with inclined water-deflecting guides or conduits whereby the flow of water is caused to rotate the float, combined with a valve operated by said float, substantially as set forth. 55

2. A float provided with inclined water-deflecting guides or conduits whereby the flow of water is caused to rotate the float, combined with a valve operated by said float, a stationary screw-threaded part, and a correspondingly-screw-threaded part engaging the former and carried by the float, substantially as set forth. 60

3. The combination, with a casing having an entrance for fluid, of a float carrying a valve adapted to close said entrance, the latter devices being provided upon the top opposite to the entrance with ribs substantially tangential to circles described about the vertical axes of the float and valve, whereby the inflow of fluid is caused to rotate the float and valve, substantially as set forth. 70

4. The combination, with a casing having an entrance for fluid, and a valve-seat, of a valve and operating-float, the latter devices being provided upon that side of the entrance on which said valve-seat is situated, with inclined water-deflecting guides or conduits, substantially as set forth. 75 80

In witness whereof I have hereunto set my hand in presence of two witnesses.

FRITZ DEIMEL.
